UNITED STATES PATENT OFFICE.

OLIVER G. SIMMONS, OF WASHINGTON, DISTRICT OF COLUMBIA, ASSIGNOR OF ONE-HALF TO KENNETH L. KINTZEL, OF TAMAQUA, PENNSYLVANIA.

AEROPLANE.

993,724.

Specification of Letters Patent. Patented May 30, 1911.

Application filed August 13, 1910. Serial No. 577,038.

To all whom it may concern:

Be it known that I, OLIVER G. SIMMONS, a citizen of the United States, residing at Washington, in the District of Columbia, have invented a new and useful Aeroplane, of which the following is a specification.

This invention relates to aeroplanes, of either the monoplane or biplane type, and has particular reference to specific improvements in devices for stabilizing the machine without warping or distorting the forms of the main planes, all as will be hereinafter fully described and claimed, and illustrated in the accompanying drawings, in which

15 Figure 1 is a plan view of a biplane machine to which my improvements are connected; Fig. 2 is a front elevation and Fig. 3 is an end elevation of the same; Fig. 4 is a diagrammatic perspective view of the 20 stabilizing devices in a preferred form thereof, detached from the other parts of the machine, the movable parts being shown in different positions by distinctive character of lines; Fig. 5 is a sectional detail of certain parts hereinafter referred to; Fig. 6 is 25 a detail hereinafter described, and Fig. 7 is a perspective view of a modification of the invention.

Throughout the following detailed description and on the several figures of the drawings similar parts are referred to by like reference characters.

In aerial navigation when aeroplanes are employed it is well understood that in order 35 to maintain proper equilibrium, when overcoming irregular impulses of the wind or in turning, it is necessary to vary the effective angles of the respective lateral ends of the machine, the means for accomplishing 40 this purpose being under the immediate control of the operator. In this machine I provide for the above-mentioned control by employing a pair or sets of pairs of independent planes, which may be located at 45 any convenient places with respect to the main planes, but preferably beyond the ends of the main planes at the extreme sides of the aeroplane.

As illustrated diagrammatically I have 50 shown a flying machine including a pair of main supporting planes 10 and 10' held properly spaced one above the other by suitable braces 11 and maintained in proper rigid relation by guy wires 12. These 55 planes and associated parts may be made of

any suitable materials now well known in the art but preferably are of a rigid construction.

At 13 I show a horizontal plane carried by the front part of the machine, adapted for controlling the elevation thereof, and at the rear part of the machine I show a horizontal plane 14 and vertical rudder 15. Any convenient or desirable form of propeller or propellers and driving means therefor may be employed but since they form no part of this invention they are not illustrated.

In carrying out this invention in a practical embodiment, but which will be understood as being illustrative of one of many adaptations which may be resorted to, I have shown in the drawings a pair of auxiliary or stability planes at each side of the machine, the planes of each pair being connected together for simultaneous and harmonious operation, and both pairs of stability planes being connected by means under the direct control of the operator whereby they may be moved in unison in either direction. I show a pair of stability planes 16^a and 16^b at one end of the machine, say at the left of the operator, and the other pair 17^a and 17^b are at the right of the operator. The stability planes of each pair are rigidly guyed to each other so as to maintain proper parallelism between them and yet so as not to interfere with the variation in their position with respect to the main planes of the machine. A guy 18 also is shown extending from the outer end of the axis of the upper plane of each pair diagonally inwardly and downwardly and connected to a beam or strut in the main part of the machine, the purpose of such guy being to increase the rigidity of that pair of stability planes with which it is associated. The stability planes are shown as being normally in alinement with the main planes of the machine, but it is not my purpose to be limited to such positions.

As a suitable means for swinging the stability planes on their axes I show a pair of rock shafts 19 and 19', in alinement with each other and lying substantially in the lower main plane 10 and extending laterally from the region of the center of the machine. Said shafts are journaled in suitable fixed bearings in the main frame. Each of said shafts has direct connection with a pair of the aforesaid stability planes, in this

instance such connection being directly with the lowermost of each pair, so that when either rock shaft is rotated in either direction the stability planes connected therewith will be swung in a corresponding direction on their axes, the axis of the uppermost of the pair of stability planes being parallel to the rock shaft and practically in alignment with the axis of the uppermost main plane 10'. The said uppermost stability plane is shown as having a short axis journaled at 20 to the extreme end of the plane 10'. As a suitable means for operating said shafts I prefer to journal on their meeting ends a sleeve or frame 21, just outside of which are connected to the respective shafts 19 and 19' a pair of miter gears 22 and 22', and meshing with both of said gears is an idler gear 23 to which is connected a lever 20 or rock shaft 24 which may extend forwardly from the sleeve in normal position or in any other suitable direction but preferably on the side of the main rock shaft adjacent to the operator.

25 In that form of the invention wherein the rock shaft 24 is connected to the gear 23 for the rotation thereof in either direction, any suitable means may be connected to the rock shaft, such as an auxiliary lever 24^a under the control of the operator whereby when the said auxiliary lever is swung to the right or left the rock shaft 24 will be correspondingly rotated and the shafts 19 and 19' rotated in opposite directions.

25 As viewed in Fig. 4 if the lever 24^a be connected rigidly with the gear 23 and said gear be journaled for rotation with respect to the sleeve 21 it is possible and perhaps may be desirable on the part of the operator 40 for him to so control the stability planes as to cause them not only to move simultaneously in opposite directions but also to move in the same direction or even for one to be held stationary while the other may 45 be moved in either direction. That is to say if the lever 24^a projects upwardly and the operator draws upon it rearwardly he will cause the gear 23, and the other gears to swing bodily together on the axes of the 50 shafts 19 and 19', causing the stability planes to swing upwardly in front and downwardly in the rear. Likewise a forward movement of the lever would act to depress the stability planes in front, tending 55 to cause the machine to descend. If the lever 24^a be swung directly to one side or the other the gears 22 will be rotated simultaneously in opposite directions just as before described causing the stability planes to 60 move simultaneously in opposite directions. Again, it is possible for the lever 24^a to be moved either forwardly or rearwardly in combination with a lateral movement so as to cause the gear 23 to roll upon one of the 65 gears 22, leaving the latter stationary and

driving the other gear 22 at an increased speed in the direction determined by the direction of movement of the lever.

In Fig. 6 I have indicated a further adaptation of my improvement whereby the lever 70 24^a is extended upwardly into loose positive connection with the back rail or support of the seat of the operator, whereby the movements of the operator which he makes during the controlling of his machine will serve 75 automatically to operate the stability planes and in directions consistent with the said natural movements of his body. More definitely stated should it be necessary to depress the left side of the machine for instance the operator will naturally swing his body toward the left. By having this direct connection to the operator's seat the movement of his body toward the left will automatically tend to swing the lever 24^a in 80 85 the same direction and with a result that the stability planes on the left side of the machine will be turned to depress that side of the machine. Any suitable means may be employed for connecting the seat to the machine and the said lever to the seat. Any convenient means may be employed for operating the elevating plane 13 and the rudder 15, and under certain circumstances it may desirable to connect one or the other or 90 both of the controlling means of the elevating plane and rudder with the main controlling lever 24.

Fig. 7 illustrates diagrammatically a modification of the device in which the 100 main stationary planes 10 and 10' are displaced by the stability planes, which are made correspondingly large enough for this purpose. As in the other modifications however the stability planes have the same relation to each other and are controlled in a 105 manner similar to that above described. The stability planes 16^c and 16^d are connected for simultaneous movement in either direction and the stability planes 17^c and 17^d are operated in an opposite direction by 110 means of the gear connection heretofore described. This form of the invention will also preferably have coöperating with it the elevating plane 13 and the rudder 15.

I claim:

In a flying machine, the combination 115 with elevating and steering devices, of pairs of stability planes on opposite sides of the machine, each pair of planes being connected for simultaneous movement in either direction, and means for rotating said pairs of planes simultaneously in opposite directions, said means including a pair of coaxial rock shafts, a pair of gears connected to the respective shafts, an intermediate gear meshing with said first-mentioned gears, and means under the direct control of the operator for automatically controlling the movements of said intermediate gear, said con- 120 125 130

trolling means including an operator's seat having a back support, a shaft connected to and extending forwardly from said intermediate gear, and a lever extending up-
5 wardly at an angle from said shaft directly to and having loose positive engagement with said back support of the seat.

In testimony whereof I have hereunto set my hand in the presence of two witnesses.

OLIVER G. SIMMONS.
